C. G. HAWLEY

LOCOMOTIVE BOILER

Filed May 13, 1922

Inventor

UNITED STATES PATENT OFFICE.

CHARLES GILBERT HAWLEY, OF CHICAGO, ILLINOIS, ASSIGNOR TO LOCOMOTIVE FIRE-
BOX COMPANY, OF CHICAGO, ILLINOIS, A CORPORATION OF DELAWARE.

LOCOMOTIVE BOILER.

Application filed May 13, 1922. Serial No. 569,654.

To all whom it may concern:

Be it known that I, CHARLES GILBERT HAWLEY, a citizen of the United States, and a resident of Chicago, Cook County, Illinois, have invented certain new and useful Improvements in and for Locomotive Boilers, of which the following is a specification.

My invention relates to improvements in locomotive boilers, with particular reference to improvements in the internal fireboxes thereof. The object of the invention is to improve the steaming capacity and the efficiency of locomotive boilers. To this end I equip the same with water-steaming-and-circulating walls, which occupy the firebox of the boiler, and which accomplish the same purposes and perform the same functions as do the well known Nicholson thermic siphons, with some improvements. As will presently appear, my invention comprises a locomotive boiler firebox with its mud or foundation ring in combination with one or more substantially triangular water-steaming-and-circulating walls, which I erect between said mud ring and the crown sheet of the firebox and each of which at its lower end is in direct communication with the throat of the boiler, while its top opens freely through the crown sheet of the firebox. The details of my invention will be clearly comprehended on reference to the accompanying drawings, in which Fig. 1 is a vertical longitudinal section of a locomotive boiler firebox embodying my invention; Fig. 2 is a transverse vertical section thereof on the line 2—2 of Fig. 1, and Fig. 3 is a combined plan view and horizontal section of the firebox on the line 3—3 of Fig. 2.

The firebox 1 here shown is of the combustion chamber type. My invention, by a slight modification in the shape of the water-steaming-and-circulating wall, is quite as well adapted to fireboxes of the straight flue-sheet type. The crown sheet of the firebox is marked 2, the back sheet 3, the side sheets 4, 4, and the throat sheet 5, and the mud or foundation ring is marked 6. The throat sheet 5 may also be taken as representing the lower part of a plain flue-sheet. The part marked 7 will be recognized as the barrel of the locomotive boiler and the part marked 8 as the wrapper or shell of the firebox. Between the firebox and the wrap-

per are the following water spaces or legs, to wit, the throat or front water leg 9, the side legs 10—10 and the back water leg 10'. The latter contains the fuel door 12. The firebox grate is marked 13, and 14 represents the ash pan. The firebox here shown is of the "wide" type. I have selected this as the more common type, but it will be understood that my invention is also applicable to fireboxes of the "narrow" type and to fireboxes of the extra wide types, the only difference being in the number of vertical water walls or semi-partitions employed.

The water wall "W" referred to may be formed from a single sheet of firebox plate, folded upon itself after the manner followed in making the Nicholson thermic siphon; or it may be formed from two sheets W', W', the edges of which are flanged and welded together, as indicated at points W² in Fig. 3. These sides or sheets W' are spaced apart to form the water spaces W³ and are connected by many closely spaced stay-bolts, W⁴. In side-elevation the water wall has a generally triangular form or shape. The triangle, obviously, is inverted, presenting its base, W⁵, to the crown sheet 2, while its apex is presented virtually at the mud ring 6. W⁶ represents the closed bottom of the wall W, the same being inclined upwardly and rearwardly from the mud ring to a juncture with the crown sheet 2. The forward edge, or closed end, W⁷ of the wall W, starts at a point 5' on the throat 5, considerably above the mud ring 6. From that point the edge curves backwardly and upwardly and finally merges with the crown sheet 2 at the point 2'. It is possible to have the bottom line W⁷ start directly at the mud ring 6 and extend thence to the crown sheet, but by preference I provide the mud ring with a tongue or extension 6', which constitutes a separate bottom for the lower extended portion W⁹ of the wall. The grate bears the reference character 13.

The firebox is assumed to be provided with the usual blow-off cocks; and, in addition, a blow-off cock 11 is provided for each of the water walls, the same being placed in the mud ring extension 6' close to the rear end thereof, the better to discharge any accumulation of sediment which may lodge in the bottom of the water wall. The parts 11', Fig. 2, are the operating stems belonging to the blow-off cocks 11.

It will be understood that the lower for-

ward end W^{10} of the water wall passes through an opening in the throat or flue-sheet 5 and is autogenously welded thereto. The lower edges of the water wall are 5 brought down and riveted to the mud ring extensions or tongues, 6', following usual boiler practice. The upper edges W^x of the water wall side sheets and ends are flanged outwardly as well shown at W^y in Fig. 3 10 and are autogenously welded to the edges of pre-formed openings in the crown sheet. After being so welded the crown stays are placed in position, those rows of stays which are adjacent the walls being fastened in the 15 top flange W^y thereof.

It will now be understood that the lower end of the wall W is in open communication with the throat 9 of the boiler, the free flow of water therethrough being interrupted 20 only by the presence of the stay-bolts necessarily positioned therein. Likewise the upper end or top of the wall W presents an open slot, W^z , which appears to be in the crown sheet 2 itself, the flange W^y of the 25 wall having become a part of the latter. The water wall (or walls) forms convenient supports for the firebox arch A indicated by dotted lines in Fig. 1. The arch is omitted from Fig. 2 for the sake of clearness. When 30 desired the lower part of the part A' of the arch may be vertical and the part of the grate which is forward of the wall A' may be blanked off as indicated at A^2 (see Fig. 3) after the manner of a so-called 35 Gaines firebox. Frequently this will be found desirable. The arrangement is very clearly shown in Fig. 3, wherein it will also be observed that the arch is supported by lugs 15 that project from the water walls 40 and side sheets.

To those skilled in the art it will be observed that all problems of expansion and contraction are effectively cared for in this design, the projections or tongues 6' of the mud ring being fixed only at one end are free to move slightly as the lower part of the siphon contracts or expands. For the rest, the vertical and longitudinal expansion of the water wall so nearly conforms 45 to the simultaneous expansion and contraction of the remainder of the firebox as to 50 occasion no trouble.

When an intense fire is maintained in the firebox the boiler water is heated and converted into steam upon every exposed surface thereof, including the surfaces of the 55

water wall or walls. In consequence, the cooler heavier water flows rapidly into the lower part of the water wall, following the path of the arrows in Fig. 1. The water being heated and much evaporated, rises rapidly and flows into the upper part of the boiler through the open top of the wall. It will be observed that the opening at the top of the wall is so much greater than that at the bottom as to permit a full and free expansion of the water, so that the column of water rising from the water wall is not so vigorous as to objectionably penetrate the steam space or prime the steam. 60 65 70

When the water level in the boiler is allowed to fall to or below the top of the crown sheet the vigorously ascending column of water within the water wall spreads over the top of the crown sheet and thus affords full protection against a dangerous explosion. 75

Having thus described my invention, I claim as new and desire to secure by Letters Patent:

1. In combination with a locomotive boiler firebox including a crown sheet, a throat sheet and a mud ring having a tongue extending rearwardly from said throat sheet, a substantially triangular upright flat tubular water wall having an inlet mouth at one end including a part embracing said mud ring tongue and a part opening through the throat sheet and communicating with the bottom water space of the boiler, the other end of the water wall opening through the crown sheet and communicating with the top water space of the boiler. 80 85 90

2. In combination with a locomotive boiler firebox including a crown sheet, a throat sheet and a mud ring having a tongue extending rearwardly from said throat sheet, a substantially triangular upright flat tubular water wall having an inlet mouth at one end including a part embracing said mud ring tongue and a part opening through the throat sheet and communicating with the bottom water space of the boiler, the other end of the water wall opening through the crown sheet and communicating with the top water space of the boiler, and a blow off cock positioned in the mud ring tongue and through which sediment may be discharged from said water wall. 95 100 105

In testimony whereof, I have hereunto set my hand this 6th day of May, 1922.

CHARLES GILBERT HAWLEY.
